UNITED STATES PATENT OFFICE.

THORVALD MAIJGREN, OF ROCHESTER, NEW YORK.

CYSTOSCOPE.

Application filed December 16, 1927. Serial No. 240,552.

The present invention relates to cystoscopes and more particularly to devices of this character which are designed to serve a variety of purposes while inserted in place within the body of a patient, one object of the invention being to provide an apparatus of this nature having a simple and effective means for connecting various operating instruments thereto. Another object is the provision of such an apparatus which will permit relatively rapid and precise interchange of operating instruments with a minimum amount of disturbance and pain to the patient. A further object is the provision of simple and effective means for rendering the cystoscope fluid tight when an operating instrument has been inserted therein.

To these and other ends the invention resides in certain improvements and combinations of parts, all as will be hereinafter more fully described, the novel features being pointed out in the claims at the end of the specification.

In the drawings:

Fig. 1 is an elevation of a cystoscope embodying the present invention;

Fig. 2 is a fragmentary detail view of the lower end of the device with certain parts shown in section to illustrate an instrument such as a catheter, in place therein;

Fig. 3 is a fragmentary sectional detail showing a portion of the parts shown in Fig. 3 but on a larger scale;

Fig. 4 is a detail of the lower end of the cystoscope showing the arrangement of the threaded section thereon; and

Fig. 5 is a horizontal section taken substantially on line 5—5 of Fig. 2.

Similar reference numerals throughout the several views indicate the same parts.

The present embodiment of the invention provides a device of the class described designed for easy and effective interchangeability of operating instruments therein to insure fluid tight connections for the parts and at the same time substantially minimizing the shock and pain usually attending the interchanging operation. To this end the invention as disclosed is embodied in a cystoscope or similar instrument, the casing of which has a fitting at the end thereof to which various instruments such as catheters, lithotrites, stone searchers, etc., after insertion therethrough, may be connected in a ready, secure and safe manner.

Referring more particularly to the draw-

ings there is shown at 10 in Fig. 1 the tubular casing of a cystoscope in the end of which a catheterizing instrument 11 has been inserted.

The cystoscope, in its general aspects, may be of conventional form, being provided with a detachable bougie 12 of a more or less usual form for assisting the penetration of the device within a natural orifice of the body, such as the urethra, in cases of stricture of such orifice. The upper end of the tubular casing 10 of the device is provided with a suitable fenestral opening 13 to permit egress of an operating instrument into a body cavity, such as the bladder, in a manner which is well known to persons skilled in the art.

The lower end of the tubular casing 10 is provided with means for securing an operating instrument thereto so as to provide a fluid tight joint, while at the same time making possible the removal of one instrument and the insertion and connection of another while the device is in the patient's body without shock or jar and the accompanying pain and discomfort to the patient. For this purpose, in the present embodiment of the invention, there is provided at the lower or outer end of the casing 10, an enlarged tubular portion 14 having a bore 15 which is of a size to snugly fit a plug part 16 of the catheter 11 and similar plug parts on other instruments to be used with the device.

In order to insure the proper positioning of the instrument inserted in the cystoscope, suitable means are provided for guiding the plug 16 within the bore 15 and for preventing its turning therein. In the present instance this function is effected by providing an axially disposed rib 17 on the plug 16 which cooperates with a similarly shaped depression in the inner wall of the bore 15.

Suitable means are provided for clamping the catheter or other instrument in fixed relation to the cystoscope. In the present instance the tubular portion 14 of the device is provided with an outer threaded part 18 near its open end with which a similarly threaded inner part on a clamping nut 19 on the catheter 11 is adapted to engage.

The catheter shown herein is of the type having a double channel which can be used for irrigating purposes as well as for drainage. The channels or irrigating tubes 20 and 21 pass through the plug portion 16 and up through the tube 10 to a point adjacent the opening 13. The lower parts of the tubes 20 and 21 terminate in curved ends, one be-

ing shown at 22 in Fig. 1, and are adapted to have attached thereto a pair of rubber tubes, not shown, for conducting fluid to and from the tubes 20 and 21.

5 Along the side of the tubes 20 and 21 there is provided a sight tube 23 with which a lens system, not shown, is adapted to be associated in a well known manner.

10 Knobs 24 and 25 are shown for manipulating certain moving parts of the device in a manner which is generally understood.

15 Means are provided for holding the nut 19 in permanent relation to the catheter. In the present instance, the plug portion 16 on the catheter is constructed with a collar 26 having a concentric projecting portion 27 thereon of smaller diameter than the collar and of a size to fit accurately within an inwardly projecting flange or collar 28 on the 20 nut 19 so as to center the nut properly with relation to the plug portion 16. A retaining ring 29 is provided in the present instance for engaging the flange or collar 28 to prevent its movement away from the centering portion 27. This retaining ring is suitably secured to the collar 26 by means of a plurality of countersunk-head machine screws 30, the heads of which lie flush within the upper portion of the retaining ring.

30 In order to insure a fluid tight connection between the parts, a suitable sealing means, such as a gasket 31, is provided between the retaining ring 29 and the end surface of the tubular portion 14 of the casing. This gasket 35

may be of any desired composition such as fibre or rubber and is preferably held more or less permanently on the retaining ring as by means of a flange portion 32 projecting upwardly around the edge of said ring and 40

engaging the outer edge of the gasket 31. The flange 32 thus serves to retain the gasket on the ring 29 and further tends to prevent undue spreading of the gasket due to any pressure exerted thereon, in connecting the catheter with the cystoscope. The space between the retaining ring 29 and the collar 26 is made somewhat greater than the thickness of the flange 28 on the nut to allow for a certain amount of freedom for axial movement 50 of the nut 19 relatively to the plug portion 16. This also allows for a slight amount of rocking movement of the nut 19 to further facilitate starting of its threads upon the threaded part 18.

55 The nut 19 is preferably provided with a plurality of depressions 33 around its periphery to facilitate holding and turning the nut with the fingers.

60 It will be understood that other instruments which are to be used with the cystoscope will be provided with the same form of attaching means as has been illustrated in connection with the catheter so that they will all be readily interchangeable.

65 In the use of the device in diagnosis and

treatment of the bladder, the cystoscope is inserted into the urethra of the patient in the usual manner. After an inspection of the affected parts with the aid of the usual lamp and lens system of the cystoscope, if it is desired to use an instrument for further diagnosis or treatment of the parts, the lens system is removed by carefully unscrewing the nut 19 from the threaded part 18 and withdrawing the plug portion 16 from the bore 15 of the tubular end 14. In practice the attendant grasps the tubular end 14 with one hand to hold it steady and unscrews the nut with the other hand. In this way the instrument may be removed without causing pain to the patient. The next instrument is inserted and connected in place by first inserting the plug portion 16 a short distance into the bore 15 until the nut is in a position to engage the first thread on the tubular end 14, the nut is then turned with one hand while the other hand holds the tubular end steady until the gasket comes into contact therewith. The device is then in readiness for the next operation. It is thus possible to substitute one instrument for another while the cystoscope is in place, in a manner which is extremely gentle and avoids all undesirable shocks or jars.

90 The present invention thus affords a safe, precise and relatively rapid means for interchanging the various instruments used with a cystoscope and at the same time insures a gentle and practically painless manipulation of the instruments without the removal of the cystoscope from the patient and thus greatly reduces the hazards attending the 95 operation as well as facilitating the diagnosis and operation as a whole.

100 I claim as my invention:

1. In a surgical instrument, a tube adapted for insertion within a body orifice, an instrument adapted for insertion within said tube, a plug portion on said instrument, and a portion on said tube having a bore of a size to fit said plug portion, one of said portions having threads exteriorly thereof and the other of said portions having a clamping nut associated therewith for engagement with said threads whereby said instrument is secured within said tube.

110 2. In a surgical instrument, a tube adapted for insertion within a body orifice, an instrument adapted for insertion within said tube, a plug portion on said instrument, a portion on said tube, having a bore of a size to fit said plug portion, and cooperating means on said plug portion and the inner surface of said bore for preventing turning of the plug 120 therein, one of said portions having threads exteriorly thereof and the other of said portions having a clamping nut associated therewith for engagement with said threads whereby said instrument is secured within 125 said tube.

3. In a surgical instrument, a tube adapted for insertion within a body orifice, an instrument adapted for insertion within said tube, a plug portion on said instrument fitting within the end of said tube, a clamping nut on said plug portion, threads on said tube for engagement with said nut, a retaining member for holding said nut on said plug portion, and sealing means between said retaining member and the end of said tube whereby a fluid tight joint is provided when the clamping nut is screwed upon said threads.
4. In a surgical instrument, a tube adapted for insertion within a body orifice, an instrument adapted for insertion within said tube, a plug portion on said instrument fitting

within the end of said tube, a collar on said plug portion, a clamping nut having an inwardly extending flange bearing against said collar to limit axial movement of the nut on said plug in one direction, a centering projection adjacent said collar fitting within the inwardly projecting flange on said nut to center the same relatively to said plug, a retaining ring adjacent said centering projection for engagement with the flange on said nut to limit axial movement thereof in the other direction on said plug, and sealing means on said retaining ring adapted to bear against the end of said tube when the clamping nut is in engagement with the threads thereon.

THORVALD MAIJGREN.
